United States Patent Office.

WILLIAM ADAMSON, OF PHILADELPHIA, PENNSYLVANIA.

Letters Patent No. 65,038, dated May 28, 1867.

IMPROVEMENT IN APPARATUS FOR SECURING PULVERIZED AND OTHER MATERIALS TO PAPER.

The Schedule referred to in these Letters Patent and making part of the same.

TO ALL WHOM IT MAY CONCERN:

Be it known that I, WILLIAM ADAMSON, of Philadelphia, Pennsylvania, have invented certain Apparatus for Securing Pulverized and other Material to Paper and other Fabrics; and I do hereby declare the following to be a full, clear, and exact description of the same, reference being had to the accompanying drawing, and to the letters of reference marked thereon.

My invention consists of two endless aprons in combination with certain rollers, so arranged that the aprons will converge towards two presser-rollers, as described hereafter. The paper or other fabric on the fluid surface of which the pulverized or other material has been deposited may pass between and traverse with the two converging aprons, by which a gradual pressure is imparted to the fabric and its coated surface, and the accumulation of ridges or masses of the material at different points on the fabric prevented.

In order to enable others to make and use my invention, I will now proceed to describe the manner of carrying it into effect. On reference to the accompanying drawing, which forms a part of this specification—

Figure 1 is a vertical section of the apparatus.

Figure 2, a plan view.

Figure 3, a diagram illustrating part of the apparatus heretofore used.

A is the frame of the machine, at one end of which turn two rollers, B and B', at the opposite end two similar rollers, C and C', and near the latter two intermediate rollers, D and D'. An endless apron of vulcanized gum elastic, or of leather or suitable fabric, passes round the upper roller, B and C, and over and under the intermediate roller, D, a similar endless apron passing round the lower rollers B' and C', and under and over the intermediate roller D'. The rollers B and B' are situated at a distance apart from each other. The rollers D and D' are so close together that the two endless aprons, E and E', are compressed between them, one of these rollers being so weighted, or otherwise so acted upon by suitable appliances, as to compress the aprons with more or less force against the other roller. The two rollers C and C' are a short distance apart from each other, but nearer together than the rollers B and B'. The rollers at one end of the machine are so geared together, and so driven, that the endless aprons will traverse in the direction pointed out by the arrows, fig. 1.

Rollers have been heretofore used in the manufacture of sand and emery-paper for compressing the pulverized material on to and into the glued surface of the paper or fabric, as shown in fig. 3, for instance, where y and y' represent two rollers, and x the paper or fabric traversing in the direction of the arrow. The pulverized material is scattered as evenly as possible over the glued surface of the paper, and is pressed into the latter by the rollers. The objection to this, the ordinary arrangement, is the tendency of the material to accumulate in a ridge or mass, t, in front of the roller, and this mass will occasionally pass between the rollers, so that more of the material will be accumulated at some points on the paper than at others. My invention has been designed to obviate this difficulty.

It will be seen, on reference to fig. 1, that owing to the peculiar arrangement of the rollers, the endless aprons converge from the rollers B and B' to the rollers D and D', leaving a space gradually diminishing in size for the admission of the paper or fabric x, the pulverized material on the glued surface of which is submitted to a gradual pressure between the two aprons before it receives its final pressure at the point where the aprons pass between the rollers D and D'. From this point the aprons diverge, so that the paper can pass freely from the machine without being subjected to further pressure. It will be seen, without further description, that as the pressure is applied gradually by means of the converging aprons, no objectionable ridges or accumulations of the pulverized material can occur on the paper.

Hitherto I have alluded to the apparatus as applied to the manufacture of sand and emery-paper; it can, however, be used to advantage in other manufactures in which it is desirable to spread evenly over fabrics, and to secure to the same, pulverized or other material. In the manufacture of velvet wall-paper, for instance, the short fibres termed "flock" can be applied to the glued or pasted surface of the paper by the aid of the apparatus.

I claim as my invention, and desire to secure by Letters Patent—

The two endless aprons E and F, in combination with rollers so arranged that the said aprons will converge towards pressure-rollers D and D', as and for the purpose described.

In testimony whereof I have signed my name to this specification in the presence of two subscribing witnesses.

WM. ADAMSON.
